UNITED STATES PATENT OFFICE.

BENJAMIN OWEN, OF DAYTON, OHIO.

IMPROVEMENT IN SAWING-MACHINES.

Specification forming part of Letters Patent No. 128,420, dated June 25, 1872.

Specification describing a certain Improved Adjustment for Circular Saws, invented by BENJAMIN OWEN, of Dayton, in the county of Montgomery and State of Ohio.

My invention relates to a device for the adjustment of the swinging frame used to support circular saws.

Figure 1 is a side elevation of the machine. Fig. 2 is a view of the locking device in its relation to the swinging frame and the racks. This drawing in scale is twice that of Fig. 1.

A represents the saw-frame, which is constructed in the usual manner. To the rear of the frame are secured the arms G, one on each side of the frame. These arms are provided with pivots for the ends of the frame B, and the centers of which form bearings for the counter-shaft. The dotted lines at H show the position of the pulley on the counter-shaft. A belt connects this with the pulley on the saw-mandrel. To the forward part of the frame are secured segmental racks D, one on each side having a series of cogs in front, and an aperture extending nearly the entire length of the racks. The swinging-frame B is constructed in the usual manner, having projecting parts, shown by dotted lines at m, which serve as bearings for the saw-mandrel. To the front and under side of this frame are secured the hangers B¹ and B², that of B¹ being on the near side, and B² on the opposite side. These hangers form the bearing for the shaft of the pinions F on each side, and support the tightening-rod E at each end. The pinions gear into the rack, and outside of the near pinion the

shaft terminates in a square end for the orifice of the crank I. (See Fig. 2.) By means of the crank the pinions are made to rotate, and thus the saw is carried up or down, as may be desired. The tightening-rod E, Fig. 2, has a screw on each end. The screw on the left end enters a female screw in the part B¹, and the screw to the right enters the nut L. This nut has a flanged part, which rests against the side of the frame, and the other part rests loosely within the aperture of the rack, which prevents its turning. The head E' is flanged and terminates in a square for the crank. The rod passes through the aperture of the rack, and the opposite end passes through a circular orifice in the part B². The pinion-shaft and tightening-rod are both operated by cranks at the same time, one being operated by the right and the other the left hand. On turning the crank to the right the rack is clamped between the head E' and part B¹, and the nut L is brought tightly against the rack on the opposite side; this locks the swinging frame and holds the saw at any desirable elevation. A counter movement releases the frame.

I claim as my invention—

The combination and arrangement of the rod E, nut L, hangers B¹ B², pinions F, racks D, and swinging circular-saw frame B, substantially as described.

BENJAMIN OWEN.
